Albert C. Babcock

UNITED STATES PATENT OFFICE.

ALBERT C. BABCOCK, OF NEW HAVEN, CONNECTICUT.

IMPROVED CURTAIN-FIXTURE.

Specification forming part of Letters Patent No. **26,824**, dated January 17, 1860.

To all whom it may concern:

Be it known that I, ALBERT C. BABCOCK, of the city and county of New Haven, in the State of Connecticut, have invented a new and useful Improvement in Operating Curtains for Coach-Doors, &c., as a new article of manufacture; and I do hereby declare that the following is a full, clear, and exact description of the construction, character, and operation of the same, reference being had to the accompanying drawing, which makes part of this specification, which drawing represents a curtain and its appendages for a coach-door, &c., as attached.

My improvement consists in the method of so connecting an india-rubber spring to the curtain-roller that the curtain may be drawn down when desired, and detained in any desired position by the ratchet attachment, and be rolled up by the spring when desired.

I make the coach door or frame A A in any of the usual ways or forms for attaching curtains by rollers.

I make the roller for the curtain of a solid rod or a tube, as I find most convenient, as indicated at B. On one end of this roller B, I fix a ratchet-wheel, as shown at c, in which I use a ratchet, as shown at d, to secure the curtain at the desired height at any time, and at the other end I fix a pulley, as shown at e, to enable the spring to act on the roller to roll up the curtain when the ratchet is released.

I make the curtain F of any suitable material, and attach it to the roller B in any convenient way.

I attach the roller B to the frame by suitable knobs or studs at a and b.

I use an elastic india-rubber spring, as shown

at C, one end of which I attach by a clasp, as at g, or by any other convenient means, and carry the other end over an anti-friction roller, as at h, and secure it to the pulley e.

Having made the several parts and connected them, as before described, (the curtain being fitted to roll up on the side of the roller next to the coach-door, and its lower edge steadied by cords, as at l and l,) if I wish to draw the curtain down I do so by means of the tassel D, (as the ratchet d will allow the roller B to revolve in that direction,) when the spring C will be wound around the pulley e, (its elasticity allowing of sufficient expansion,) and the ratchet d will detain the roller B in the desired position; and if I wish the curtain roller up I trip the ratchet d by means of the tassel E, when the spring C will by its contraction revolve the roller B and roll up the curtain.

I am aware that curtains have been rolled up by metallic springs in various ways, and that india-rubber springs have been used for many purposes, and that the ratchet attachment has long been used on curtains. I therefore do not claim either of these, as such, as my invention; but

What I claim as my invention, and desire to secure by Letters Patent, is—

The combination of the long india-rubber spring C with the curtain-roller B and its appendages, when the whole is constructed, arranged, and made to operate substantially as herein described and set forth.

ALBERT C. BABCOCK.
